(57) **CLAIM**

The ornamental design for a cell phone as shown and described.

DESCRIPTION

The file of this patent contains at least one drawing/photograph executed in color. Copies of this patent with color drawing(s)/photograph(s) will be provided by the Office upon request and payment of the necessary fee.

Fig. 1 is a front perspective view of a first embodiment of a cell phone;

Fig. 2 is a rear perspective view of the first embodiment of the cell phone;

Fig. 3 is a front elevation view of the first embodiment of the cell phone;

Fig. 4 is a rear elevation view of the first embodiment of the cell phone;

Fig. 5 is a left side elevation view of the first embodiment of the cell phone;

Fig. 6 is a right side elevation view of the first embodiment of the cell phone;

Fig. 7 is a top plan view of the first embodiment of the cell phone;

Fig. 8 is a bottom plan view of the first embodiment of the cell phone;

Fig. 9 is a front perspective view of a second embodiment of a cell phone;

FIG. 10 is a rear perspective view of the second embodiment of the cell phone;

FIG. 11 is a front elevation view of the second embodiment of the cell phone;

FIG. 12 is a rear elevation view of the second embodiment of the cell phone;

FIG. 13 is a left side elevation view of the second embodiment of the cell phone;

FIG. 14 is a right side elevation view of the second embodiment of the cell phone;

FIG. 15 is a top plan view of the second embodiment of the cell phone; and,

(Continued)

FIG. 16 is a bottom plan view of the second embodiment of the cell phone.
